Loretta, Warren, Mich.

Filed July 20, 1965, Ser. No. 86,217

Term of patent 14 years

(Cl. D34—5)

Fig. 2.

FIG. 1 is a perspective view of a physical exercising apparatus showing our new design;

FIG. 2 is a perspective view, taken from the left rear of FIG. 1; and

FIG. 3 is a top plan view taken on FIG. 2 after rotation of approximately 60 degrees in the counter-clockwise direction.

The dominant features of our new design reside in the portion shown in full lines.

We claim:

The ornamental design for a physical exercising apparatus, substantially as shown and described.
